UNITED STATES PATENT OFFICE.

JACOB B. AMHERST, OF LOS ANGELES, CALIFORNIA.

DESIGN FOR A TOY BALLOON.

51,036.

Specification for Design.

Patented July 17, 1917.

Application filed May 15, 1917. Serial No. 168,896. Term of patent 7 years.

To all whom it may concern:

Be it known that I, JACOB B. AMHERST, a subject of the King of England, residing at Los Angeles, in the county of Los Angeles and State of California, have invented a new, original, and ornamental Design for Toy Balloons, of which the following is a specification, reference being had to the accompanying drawing, forming part thereof.

Figure 1 is a side elevation of a toy balloon, showing my new design.

Fig. 2 is a top plan view of the same.

I claim:

The ornamental design for a toy balloon, as shown.

In testimony whereof I affix my signature in presence of two witnesses.

JACOB B. AMHERST.

Witnesses:

EMOLYN D. CAVENDER,
ROBERT L. WARE.
